UNITED STATES PATENT OFFICE.

WILLIAM ESTY, OF LACONIA, NEW HAMPSHIRE, ASSIGNOR OF TWO-THIRDS
TO LEWIS F. BUSIEL, OF SAME PLACE, AND GEORGE W. SHERWELL, OF
LAKE VILLAGE, NEW HAMPSHIRE.

STEAM-ENGINE.

SPECIFICATION forming part of Letters Patent No. 355,814, dated January 11, 1887.

Application filed August 7, 1886. Serial No. 210,297. (No model.)

To all whom it may concern:

Be it known that I, WILLIAM ESTY, of Laconia, in the county of Belknap and State of New Hampshire, have invented certain new and useful Improvements in Steam-Engines, of which the following, taken in connection with the accompanying drawings, is a specification.

My invention relates to single-acting steam-engines, and particularly to that class of such engines in which a series of steam-cylinders arranged in a circle about the axis of the crank-shaft, and with their axes parallel to each other and to said shaft, are used; and it consists in certain novel features of construction, arrangement, and combination of parts, which will be best understood by reference to the description of the drawings, and to the claims to be hereinafter given.

Figure 1 of the drawings is a central vertical longitudinal section of my improved engine with the crank-shaft and a screw-propeller mounted thereon in elevation. Fig. 2 is a transverse section on line 1 1 on Fig. 1, with the pistons removed, and looking toward the steam-ports. Fig. 3 is a transverse section on line 2 2 on Fig. 1, looking toward the right-hand end of Fig. 1, with the pistons removed. Fig. 4 is a section through the cylinder-casting and the valve-seat on line 3 3 on Figs. 2 and 3. Fig. 5 is a section through the valve, the eccentric, and the valve-reversing oblique cylinder on line 4 4 on Fig. 1, and showing the combined valve-seat and cylinder-head in elevation. Fig. 6 is a section through the crank-shaft and the valve-reversing oblique cylinder on line 5 5 on Fig. 1, looking toward the left-hand end of Fig. 1, and showing the valve and eccentric in elevation. Fig. 7 is a transverse section on line 6 6 on Fig. 1, looking toward the left-hand of Fig. 1, and showing the interior parts beyond in elevation. Fig. 8 is a transverse section on line 7 7 on Fig. 1, looking toward right of said figure, and showing the counter-balance, the oil-pipe, and the gage for viewing the height of the oil in elevation. Fig. 9 is an elevation of the inner end of the combined crank-sleeve and duplex lever to be acted upon by the pistons through

the several connecting-rods (shown in section) 50 to cause a rotation of the shaft, and showing a portion of the casing and the guideway for preventing the rotation of said sleeve in section. Fig. 10 is a longitudinal section through the eccentric, the oblique cylinder for reversing the valve or adjusting the throw of the eccentric, and the sleeve for carrying the reversing slide and block, the cutting-plane being at right angles to Fig. 1, and showing a portion of the crank-shaft in elevation; and 55 Fig. 11 is a transverse section on line 8 8 on Fig. 10, looking toward the right of said figure.

In the drawings, A is the cylinder-casting, having formed therein a series of cylinders, a' a'' a''' &c., preferably six in number, though 65 a greater or less number may be used, if desired, arranged in a circle with their axes parallel to each other, and also having formed therein the annular exhaust-chamber b, the exhaust-passages b' leading from the exhaust- 70 ports b² in the valve-seat B to said exhaust-chamber b, the lateral exhaust-ports b³, and the annular air-chamber c, all as shown in Figs. 1, 2, 3, and 4.

The cylinder-casting A is in the form of an 75 outer rim or ring, having a central hub, A', connected to said rim by spokes c', said hub A' being bored out to form a bearing for the crank-shaft C, and having its outer or forward end made conical or in the form of a 80 frustum of a cone, against which the inner end of the crank-sleeve C abuts, as shown in Fig. 1.

B is the cylinder-head and valve-seat, in the form of an annular plate, having formed therein 85 the exhaust-ports b² and steam-ports b⁴ b⁴, and provided with the cylinder D, which projects from its inner edge and has formed upon its outer periphery at its end a male screw-thread, which screws into a corresponding female thread in the inner periphery of the rim of the casting A in such a manner as to form an annular air-space between said rim and cylinder, as shown at d in Figs. 1, 2, and 4.

E is the steam-chest, in the form of a ring, 95 having an L-shaped cross-section, to the inner periphery of which is screwed the ring E', also having an L-shaped cross-section, in such a

manner as to form a steam-tight joint between said rings at d' and form an annular air-chamber, as at d'' in Fig. 1.

F is a ring-valve, provided upon one side 5 with the annular exhaust-passage e and upon its other side with the packing-ring e' , which works against the face of the ring E' , between which and the combined valve-seat and cylinder-head B the valve F is moved.

10 The valve F is provided with a central hub or sleeve, F' , connected to the valve-ring by spokes $e^1 e^2$, which sleeve incloses the eccentric F' , as shown in Figs. 1, 5, and 6.

The eccentric F' is bored out obliquely to 15 fit the cylinder G , which is mounted upon the crank-shaft C , in such a manner that it may be moved endwise thereon, while at the same time it must be revolved therewith.

The cylinder G is bored out obliquely to 20 receive the shaft C , so that its two ends are eccentric to the axis of said shaft in diametrically-opposite directions, while at the center of its length it is concentric to said axis, all as shown in Figs. 10 and 11. A sleeve, G' , provided with the flange f and the split and threaded collar f' , is also mounted loosely upon said shaft C and secured to the cylinder G by the screws $f^1 f^2$, as shown in Figs. 10 and 11.

25 The shaft C has set therein one or more spline-keys, g , which project into corresponding spline-grooves in the cylinder G and sleeve G' , to guide said parts in their endwise movements and compel them to revolve with said shaft. The eccentric F' is in like manner 30 splined to the cylinder G , so as to be compelled to revolve therewith, and at the same time permit the oblique cylinder G to be moved endwise, through said eccentric for the purpose of stopping or reversing the engine.

35 Upon the sleeve G is fitted the block H , having formed in its upper side the T-shaped groove h , in which is fitted, so as to slide therein, the correspondingly-shaped block h' , which also has a bearing upon the crank-pin 40 h' , set in the under side of the disk H' , firmly secured to the lower end of the shaft H^2 , having its bearing in the standard or column I , screwed 45 into the casing I' , said shaft having secured to its upper end the hand-lever I^2 , by which 50 said shaft and disk may be moved about the axis of said shaft for the purpose of moving the cylinder G and sleeve G' endwise upon the shaft C , said lever being locked in any desired 55 position by the spring-actuated lever i , engaging with notches i' in the segment i^2 , secured to the upper end of the column I , as shown in Fig. 1.

The casing I' is provided with the hand-hole I^4 , closed by the cover I^5 , and also with 60 the inwardly-projecting hub I^6 , in which is formed another bearing for the shaft C . The casing I' is also provided with the exterior hub, I^7 , to which is screwed the chambered cap I^8 , in which is formed the stuffing-box I^9 , 65 as shown in Fig. 1. Within the chambered cap I^8 the shaft C has mounted thereon one or more annular steel plates or washers, i^2 , and

the split threaded collar or nut i^4 , which, after being adjusted, may be clamped to the threaded shaft by the clamping screw or bolt i^5 in a 70 well-known manner, said collar and washers serving to take the thrust of the screw-propeller J , mounted upon and firmly secured to the end of said shaft C .

The arrangement shown in Fig. 1 of the 75 drawings illustrates the application of my improved engine to driving the screw-propeller of a yacht or other boat, the stern-post of the boat (not shown) occupying the space between the propeller J and the stuffing-box I^9 ; but if 80 the engine is desired to be used for driving other machinery it is only necessary to remove the propeller and substitute therefor a suitable pulley.

The casing I' and the steam chest E are 85 secured to the cylinder-casting by a series of bolts, j , which pass through the cylinder-head and screw into the cylinder-casting A , as shown in Fig. 1.

K is a casing, which incloses the periphery 90 of the steam-chest and the flange of the casing I' , and is secured to the latter by the screws j' , the same being so formed and fitted thereto as to form an annular air-space, k , between it and said flange and the steam-chest, 95 as shown in Figs. 1 and 7.

The cylinder-casting A has bolted to its end opposite to the steam-chest E the casing L , cast in the form of a hollow cylinder, with an inwardly-projecting flange at each end, by 100 means of one of which and the bolts l said casing is secured to said cylinder-casting, and to the other of which the head L' is secured by the bolts l' , said casing being provided at its upper side with the hand-hole L^2 , which is 105 closed by the cover L^3 , as shown in Figs. 1 and 8.

A portion, C^2 , of the shaft C at the end opposite to that to which the propeller is secured, 110 is bent to an angle to the main body of said shaft, and has mounted thereon the sleeve C' , the inner end of which abuts against the conical end of the hub A' of the cylinder-casting A , and the opposite end, against one of the 115 steel washers m , loosely fitted upon the shaft, and held in place by the split threaded collar or nut m' , which, after being properly adjusted upon the threaded portion of said shaft, is firmly clamped thereto by the clamping-bolt n in a well-known manner, said washers and 120 collar serving to take the thrust of the sleeve C' occasioned by the pressure of steam upon the pistons N , which are connected by rods N' to arms O , which radiate from said sleeve C' , 125 as shown in Figs. 1 and 9.

The connecting-rods N' are attached to the pistons N and arms O , preferably by ball-and-socket joints, though said rods may have round or pointed ends and simply rest in recesses or sockets in said pistons and arms, if 130 desired.

One of the arms O of the sleeve C' has formed upon or set in its end a pin or lug, o , which is fitted to and works in a longitudinal groove,

o', formed in the lower part of the casing *L*, for the purpose of preventing the sleeve *C'* and arms *O*' from revolving about the axis of the angular portion of the shaft *C*, which forms the crank and has formed upon its extreme end the crank-pin *p*, the axis of which is parallel with the axis of revolution of said shaft *C*, and is fitted to a bearing in the light arm of the counterbalance-lever *P*, which has its bearing upon and revolves about the stud *P'*, set in the center of the head *L'* in axial line with the main body of the shaft *C*, all as shown in Figs. 1 and 8.

The exhaust-steam escapes from the chamber *b* through the pipe *b'*, from which it may be conveyed in a suitable pipe to the smoke-stack of the boiler, or to any other desired point.

Q is the steam-pipe, through which steam is admitted to the steam-chest *E*.

The chambers formed by the casings *I*' and *L* are to be partially filled with oil, so that the armed sleeve *C'* *O*, the crank-shaft *C*, and the counterbalance-lever *P*, as the engine is operated, will cause a splashing of the oil that will effectually lubricate all of the moving parts of the engine.

R *R'* is a pipe leading from the chamber formed by the casing *L* at the bottom and communicating therewith again at or near the top of said chamber, the vertical portion *R'* of which is made of glass, so that the height of the oil in said chambers may readily be seen.

The operation of my invention is as follows: The positions of the crank-shaft *C* and the pistons *N* being as shown in Fig. 1, and of the valve as shown in Fig. 5, and the chambers within the casings *I*' and *L* being properly charged with oil, if steam be admitted to the steam-chest *E* it passes directly into the cylinders *a* and *a'*, the port *b'* of the latter being wide open and that of the former having just commenced to open, and as the ports *b'* of the cylinders *a*, *a'*, and *a''* have been more or less uncovered by the inner edge of the outer rim of the annular valve *F*, so that the steam which has just done its work in said cylinders is exhausting through said ports into the annular chamber or passage *e*, and thence through the ports *b''* into the chamber *b*, and thence through the pipe *b'* to the smoke-stack of the boiler or to the open air, the direct pressure of the steam upon the pistons of the cylinders *a* and *a'* and the expansion of the steam in the cylinder *a''*, the supply of steam to which has just been cut off, acting through the connecting-rods *N'* upon those arms *O* of the sleeve *C'* which are nearest to their respective cylinders, will cause the crank-shaft to be revolved in the direction indicated by the arrows on Figs. 2, 5, and 8, the oblique or crank portion of said shaft revolving in the sleeve *M*, which itself does not revolve, but has imparted to it a sort of universal rocking motion, its inner end near the shaft *C* rolling about the conical end of the hub *A'* of the cylinder-casting *A*, and constantly changing its point of contact therewith. If it is de-

sired to reverse the motion of the shaft *C*, it is only necessary to impart to the disk *H'* a semi-revolution about its axis by means of the lever *I'*, the effect of which is to move the sleeve *G'* and the oblique cylinder *G* endwise upon the shaft *C* toward the propeller until the forward or right-hand end of the oblique cylinder *G*, as seen in Figs. 1 and 10, occupies the same position relative to one side of the eccentric that the opposite end of said cylinder now does to the other side of said eccentric.

The annular air-chamber *d*' is connected by the oblique hole *d* to the annular-air-chamber *k*, which communicates with the open-air through the vent-hole *k'*. The annular air-chamber *d* communicates by an oblique hole, *d*'' (shown in dotted lines in Fig. 4,) with the annular air-chamber *c*, which latter is in communication with the open air through the vent-hole *d*'''. These air-chambers serve to keep the engine much cooler than it otherwise would be, by virtue of the circulation of air through the same.

I am aware of the Letters Patent No. 198,535, granted to James Davies, December 25, 1877, and I do not claim anything therein shown or described.

What I claim as new, and desire to secure by Letters Patent of the United States, is—

1. In combination with a series of stationary cylinders arranged in a circle with their axes parallel to each other and a piston arranged to work in each of said cylinders, a shaft mounted in bearings with its axis parallel to and equidistant from each of said cylinders and having a portion thereof at one end bent at an obtuse angle to its main body, a sleeve mounted upon said angular portion of the shaft and carrying a series of sockets corresponding in number to said cylinders, and a corresponding series of rods connecting said sockets with the pistons in said cylinders, a plurality of collars on the angular portion of said shaft arranged to take the thrust of said sleeve, all constructed, arranged, and adapted to operate substantially as described.

2. The casting *A*, having formed therein a plurality of cylinders arranged in a circle and parallel to each other, and provided with a central hub having a conical outer end, the shaft *C*, having a portion thereof bent at an obtuse angle to its main body, the thrust-collars *m*', secured to said oblique portion, the sleeve *C'*, mounted upon the oblique crank, between said thrust-collars and the conical end of the hub *A'*, and provided with the socketed arms *O*, the pistons *N*, and a series of rods connecting said pistons and socketed arms, substantially as described.

3. The combination of the series of cylinders *a* *a'* *a''* *a'''*, &c., the shaft *C*, provided with the oblique cylindrical crank *C'*, having formed upon its end the crank-pin *p*, the thrust-collars *m* *m'*, the sleeve *C'*, provided with a series of socketed arms *O*, the pistons *N*, the series of rods *N'*, the fixed stud *P'*, and the counterbalance-lever *P*, all constructed, ar-

4
ranged, and operating substantially as described.

4. In combination with a series of cylinders arranged in a circle with their axes parallel or nearly so, a valve-seat and cylinder-head combined in one piece, an annular exhaust-chamber encompassing said series of cylinders and nearly encompassing each individual cylinder, an annular air-chamber contiguous to said exhaust-chamber and encompassing said series of cylinders, a series of steam-ports cut through said valve-seat and communicating one with each of said cylinders, and a series of exhaust passages cut through said valve-seat and extending to said annular exhaust-chamber within the circle of the inner wall of said annular air-chamber, substantially as shown and described.

5. The combination of a series of cylinders, 20 a a' a'' , &c., each provided with the lateral exhaust-port b^3 , the annular exhaust-chamber b , and passages b' , the valve-seat B , provided with the series of steam-ports b^4 and the series of exhaust-ports b^2 , and the annular valve F , 25 all constructed, arranged, and operating substantially as described.

6. In combination with a series of steam-cylinders arranged in a circle, the annular air-chambers c and d , arranged relative to said cylinders and to each other, substantially as described.

7. The annular air-chambers c and d , arranged one exteriorly of said series of cylinders and one within the circle of said cylinders and connected by the hole d^4 and communicating with the atmosphere by the vent-hole d^5 , substantially as described.

8. In combination with a series of cylinders arranged in a circle with their axes parallel, or nearly so, to each other, the shaft C , arranged with its axis equidistant from the axes of said cylinders, an annular valve-seat surrounding said shaft and forming a head to each of said cylinders with ports leading thereto, the cylinder G , mounted obliquely and movable longitudinally upon said shaft C , the eccentric F , provided with an oblique

bore to fit the cylinder G , and splined to said cylinder so as to revolve therewith, while at the same time the cylinder G may be moved 50 endwise through the same, and the annular valve F , fitted to the periphery of said eccentric and movable thereby in a plane at right angles to the axis of said cylinders, substantially as described.

9. The combination of the shaft C , the oblique cylinder G , the sleeve G' , the grooved block H , the sliding block h' , the crank-pin h^2 , the disk or crank H' , the shaft H^2 , and mechanism for moving said shaft about its axis, 55 substantially as described.

10. The steam-chest E , in combination with the L-shaped ring E' , screwed thereto and forming between said chest and ring the annular air-chamber d^2 , substantially as de- 60 scribed.

11. In combination with a series of cylinders arranged in a circle with their axes parallel, or nearly so, to each other, the shaft C , arranged equidistant from the axes of said cylinders and provided with the angular section C' , a piston and piston-rod for each cylinder, the sleeve C' , provided with socketed arms O O , and the pin or lug o , and the casing L , provided with the longitudinal guiding-groove o' , 70 all constructed, arranged, and operating substantially as described.

12. In combination with the annular steam-chest E , the annular air-chambers d^2 , surrounding the exterior of said steam-chest, and the annular air-chamber k , contiguous to and parallel with the inner wall of said steam-chest, and connected together by the oblique hole d^3 and communicating with the atmosphere by the vent-hole k' , substantially as described. 85

In testimony whereof I have signed my name to this specification, in the presence of two subscribing witnesses, on this 20th day of July, A. D. 1886.

WILLIAM ESTY.
